METHOD OF FREEZING AND PACKAGING
FOODSRobert P. Fletcher, Jr., Glencoe, Ill., assignor to
Booth Fisheries Corporation, Chicago, Ill., a cor-
poration of Delaware

Application April 14, 1938, Serial No. 201,988

5 Claims. (Cl. 62—170)

My invention relates to a method and apparatus for producing quick-frozen food products in attractive and sanitary packages.

It has long been known that many food products may be rapidly frozen while fresh and if stored at a low temperature will be fresh and palatable when thawed, in many respects equal to the product at the time it was frozen. However, the method of preparing such food products has left many things to be desired in the matter of appearance, and in the matter of cost of producing a finished package that is sightly.

An object of my invention is to provide for packing and freezing of the food product in the carton that is delivered to the consumer, and also to insure regularity in the shape of the package and the attractiveness of its appearance. Furthermore, in connection with such advantages, I provide for complete enclosure, to avoid contamination, while at the same time providing for a full size view of the contents through the transparent wrapper.

A further object is to provide for economy in cost of production by utilizing the means employed to maintain the shape of the package, for increasing the heat transfer area of contact with the refrigerating surface. By reason of the apparatus employed, I provide heat transfer surfaces on all six sides of the package, apparatus having this capacity being similar to that shown in the patent to Cooke, No. 1,614,455, owned by my assignee. My apparatus, however, is adaptable to variations in the size of the package in order to accommodate products of different kinds.

In the earlier practice in which superimposed plates were used it was found difficult to so control the weights of the respective plates that equal pressure was imposed on the product as between lower and upper series of plates. The plates are of relatively great weight, and this together with the added weight of the brine within the plates and the product resting on the plates, represented a crushing load on the lower plate, if not counterbalanced or equalized. This difficulty is avoided in my construction by interposing forms between the plates, the said forms absorbing all the pressure except that required to compress the product into the forms. This not only avoids the stated difficulty but adds the advantage of increasing the heat transfer effect of the plates due to contact thereof with the metal forms.

Essentially, the method of my invention comprises the steps of providing an open top container or box, which may have relatively thin

walls that will not greatly interfere with heat transfer. Within this package is placed a measured quantity of the food product which may be fish, meats, vegetables, etc., the product being relatively loosely packed therein and projecting a distance above the limits of the side walls of the box. The material when packed in this manner will necessarily contain many voids or air pockets, but a quantity thereof will be placed in the box that will substantially fill all parts thereof without substantial air pockets when compressed into the limits of the box. In that condition the box is placed within a form or mold, the apparatus preferably consisting of a metal grid providing a relatively large number of such molds, the box fitting the mold with substantial accuracy. The grid with its filled boxes is then placed between plates through which a refrigerating medium at a low temperature is circulated, and force exerted to move the plates toward each other. As a preliminary to this action, a sheet of waxed paper or similar material is placed over the filled boxes to protect the surfaces from any contamination. Sufficient pressure is exerted in order to bring the plates into direct contact with the grid, thus forcing the food product into all portions of the container and excluding any air therefrom. The grid will be constructed of metal of sufficient strength to resist distortion and the container will thus retain its rectangular shape. The material is quickly frozen while in this compressed condition and, when frozen, the grids are removed, the packages displaced therefrom and thereafter wrapped in a transparent wrapper that is sealed at the ends and bottom of the package. This leaves the upper surface of the material entirely visible through the transparent cover.

The invention will be more readily understood by reference to the accompanying drawings, in which:

Fig. 1 is a view of a container or box such as contemplated;

Fig. 2 shows the box filled with a quantity of material such as fish fillets;

Fig. 3 is a perspective view showing one of the grids being filled and being supported on a wheeled conveyer or truck;

Fig. 4 is a perspective view showing the freezer with its plates and the truck in position to discharge the grids thereon into the freezer;

Fig. 5 is a perspective view of the grid after having been removed from the freezer and in position to facilitate the removal of the frozen packages therefrom;

Fig. 6 is a perspective view of the wrapped packages ready for the consumer, and;

Fig. 7 is a sectional view through the freezer showing a section of the grid in place.

5 In carrying out the process, I place within the box 10 a quantity of a food product 11, the material being weighed or measured in order to make certain that a predetermined quantity is supplied that will, when compressed, completely fill 10 the box. The boxes when filled as indicated in Fig. 2 are next placed within a grid 12 consisting of a plurality of right-angularly arranged bars providing spaces 13 that are of substantially the size of the boxes 10. The grid is conveniently 15 rested on a sliding shelf 14 carried on guides in a frame 15. This frame may be in the form of a truck having wheels, as best shown in Fig. 4. After the containers have been placed as shown in Fig. 3, a sheet of paper 16 is placed over the 20 grid and its contents, and the truck is then wheeled to the freezing cabinet 17, shown in Fig. 4. The elevation of the shelves on the truck is arranged to correspond to the open spaces between the plates 18 of the freezer, these plates 25 being hollow and connected by flexible hose or pipes to a source of low temperature fluid. A hydraulic cylinder 19 is provided to lift the superimposed plates, compress the material 11 into the packages and to bring the plates into contact 30 with the grid, as best shown in Fig. 7. This insures heat transfer on all six sides of the package and enables quick freezing of the food product.

After the grids have all been placed in the freezing cabinet, the doors are closed and the 35 freezing continues until the product is frozen solid. Thereafter, the grids are removed and placed on a stand 20, shown in Fig. 5 where the packages are removed and thereafter wrapped by a machine, not shown, the package having the 40 final appearance shown in Fig. 6. Preferably, the wrapping 21 is transparent, and the sealed, overlapping edges of the wrapping are at the ends and bottom of the package, thus exposing the entire upper surface of the food product through 45 the transparent cover.

Thus the package is entirely sealed against contamination, although visible to the purchaser. Furthermore, the package is a uniform size and shape and of attractive appearance.

50 Many of the described steps of the process may be varied and others of the steps may be substituted by others; for example, the "container" used in the process may consist merely in a wrapping that serves to separate the food product 55 from the metal heat-transfer surfaces. Or I may in some cases prefer to leave both sides open, in order that inspection may be made by the purchaser of both sides instead of one only. It should be understood, therefore, that I am to be limited only to the extent of the claims submitted.

I claim:

1. The method of preparing foods for the market which consists in placing in an open top container a quantity of said food sufficient to project 65 somewhat above the side walls of the container, then placing the filled container in a form having an open top and a space, the lateral and vertical dimensions of which correspond substantially to those of the container, then placing said form and container between refrigerated plates and applying pressure to bring said plates against the form and thereby to compress the food into the 70 limits of the container, quick-freezing said food,

then discharging said form and container and separating the same, and then enclosing said package in a decorative wrapper.

2. The method of preparing foods for the market which consists in placing in an open top container a quantity of said food sufficient to project somewhat above the side walls of the container, then placing the filled container in a form having an open top and a space, the lateral and vertical dimensions of which correspond substantially to those of the container, then placing said form and container between refrigerated plates and applying pressure to bring said plates against the form and thereby to compress the food into the limits of the container, quick-freezing said food, then discharging said form and container and separating the same, and then enclosing said package in a transparent wrapper.

3. The method of preparing foods for the market which consists in placing in an open top container a quantity of said food sufficient to project somewhat above the side walls of the container, then placing the filled container in a form having an open top and a space, the lateral and vertical dimensions of which correspond substantially to those of the container, then protecting the exposed surface of the food with a removable sheet, such as paper, then placing said form and container between refrigerated plates and applying pressure to bring said plates against the form and thereby to compress the food into the limits of the container, quick freezing said food, then discharging said form and container and separating the same, then removing the protecting sheet, and then wrapping the package in a transparent material.

4. The method of preparing foods in irregular sizes and shapes for the market which consists in placing in a relatively fragile open top container a predetermined weight of said food without attempting a regular arrangement thereof whereby some portions of the food project above the side walls of the container and portions of said container are unfilled, then placing the container in a rigid metal form having an open top and defining therein a space, the lateral and vertical dimensions of which correspond substantially to those of the container, then placing said form and container between refrigerated plates and relatively moving the plates to a defined extent 45 to apply pressure and thereby to compress and rearrange the food so that the container is completely filled and then quick freezing said food while maintaining said pressure condition.

5. The method of preparing foods in irregular sizes and shapes for the market which consists in placing in relatively fragile open top containers predetermined weights of said food without attempting a regular arrangement thereof whereby some portions of the food project above the side 60 walls of the containers and portions of said containers are unfilled, then placing the containers in a unitary rigid metal form having a plurality of spaces, the lateral and vertical dimensions of which correspond substantially to those of the 65 containers, then placing said form and its associated containers between refrigerated plates and relatively moving the plates to a defined extent to apply pressure and thereby to compress and rearrange the food so that the containers are 70 completely filled, and then quick freezing said food while maintaining said pressure condition.
